UNITED STATES PATENT OFFICE.

LEONARD H. WHEELER, OF CHICAGO, ILLINOIS, ASSIGNOR TO STEWART-WARNER SPEEDOMETER CORPORATION, OF CHICAGO, ILLINOIS, A CORPORATION OF VIRGINIA.

VACUUM-FEED FUEL-RESERVE DEVICE.

Application filed May 5, 1922. Serial No. 558,753.

To all whom it may concern:

Be it known that I, LEONARD H. WHEELER, a citizen of the United States, residing in the city of Chicago, in the county of Cook and the State of Illinois, have invented certain new and useful Improvements in Vacuum-Feed Fuel-Reserve Devices, of which the following is a specification, reference being had to the accompanying drawings, 10 forming a part thereof.

The purpose of this invention is to provide an improved construction of vacuum fuel feeding device for serving the carburetor of an internal combustion engine from a low 15 fuel source, particularly adapted to provide a reserve supply of fuel. It consists in the elements and features of construction shown and described, as indicated in the claims.

In the drawings:

20 Figure 1 is a diagrammatic view showing the relative positions on an automobile of the several parts and elements consisting and concerned in the operation of this invention.

25 Figure 2 is a side elevation of the receptacles and their connections which contain the characteristic features of the invention, one of said receptacles being partly broken away, as shown in vertical section, for disclosing the interior construction.

30 Figures 3, 4, 5 and 6 are detail sections, axial with respect to its passages, of one of the valve devices designed to be operated from the driver's seat for controlling the delivery of the fuel from the ordinary or the reserve receptacle, showing respectively four positions of the valve member.

Figure 7 is a side elevation of a modified form.

40 In the structure shown in the drawings the main low level fuel supply tank or source of fuel is shown at 1. 2 is a conduit leading from the low level source to the primal or vacuum chamber, 4^a, of the vacuum fuel feed

45 device, 4, of familiar construction, having in addition to said primal vacuum chamber, 4^a, a secondary chamber, 4^b, into which the liquid fuel is delivered by gravity flow in the intervals of operation of suction by

50 which it is lifted from the main low source, 1, to said primal chamber or vacuum chamber. Said vacuum chamber is equipped in the usual manner of devices of this character, having beside the fuel inlet through

55 the pipe, 2, atmosphere inlets shown at 3 and the suction connection 6, with suction controlling valve A, and atmosphere inlet valve a, connected and operated by the snap action, C, under control of the float, B, all of familiar type and mode of operation. The 60 secondary chamber, 4^b, is connected by a pipe, 5, for delivery of the fuel to the carburetor, not shown. 7 is a reserve fuel receptacle, preferably positioned alongside the receptacle, 4, with its discharge at substantially 65 the same level as that of the receptacle, 4, said reserve receptacle being not desirably extended more than very slightly above the high liquid level of said receptacle, 4, because it is not designed that it shall be 70 filled,—and in the ordinary proper operation of the device it cannot be filled—to a higher level. The delivery pipe, 5, from the receptacle, 4, has two connections with the bottom of the receptacle, 7, one by way of the pipe, 8, in which there is interposed a check valve, 9, opening for delivery of liquid from the receptacle, 4, to the receptacle, 7, the other by way of the pipe, 11, at whose junction with the pipe, 5, there is provided a three-way valve, 12, of the turn-cock type, whose valve member, 12^a, has a diametric passage, 12^x, and a radial passage, 12^y, whereby at 75 one position shown in full line in Figure 3, direct communication is afforded through the passage, 12^x, supplying the carburetor from the receptacle, 4, while supply from the receptacle, 7, is cut off. And at another position of the valve member, 12^a, communication from the receptacle, 4, to the carburetor is 80 cut off, and communication is open for supply from the receptacle, 7. And at a third position communication is opened through the diametrical passage, 12^x, for supply to 85 the carburetor from the receptacle, 4, through the radial passage, 12^y, and the final half of the diametrical passage, 12^x, is opened for supplying the carburetor from the receptacle, 7.

90 The valve member, 12^a, has a lever arm, 13, connected with an operating crank shaft, 16, mounted upon the dash board by which the operator may adjust the valve, 12^a, according to the conditions, for supplying the carburetor either from the receptacle, 4, or from the receptacle, 7, or from both said receptacles.

95 It will be understood that the main purpose of the construction shown is to provide a reserve supply of fuel in the receptacle, 7,

to be drawn upon in any emergency causing deficiency or failure of supply, as from exhaustion of the main supply in the tank, 1, or failure of operation of the pumping devices in the receptacle, 4. And it will be understood that the valve, 12, being ordinarily set for permitting supply to the carbureter from the receptacle, 4, cutting off communication of the receptacle, 7, said receptacle, 7, will 10 become filled to its limit,—that is, to the high level limit of the receptacle, 4, by the excess pumping capacity of the device above the requirements of the carbureter, and that the capacity, therefore, of the receptacle, 7, 15 will constitute a reserve for the emergency indicated, which will be drawn upon by the operator adjusting the valve, 12, so as to put both chambers, 4 and 7, into communication with the carbureter, or only the receptacle, 7, according to the conditions of the service.

I claim:

1. In combination with a vacuum fuel feeding device which comprises a bi-cameral receptacle having a primal chamber which has suction connection, fuel supply connection and atmosphere inlet, and which discharges by gravity into the secondary chamber; a second receptacle whose chamber is 25 connected with the secondary chamber of the first receptacle; a one-way seating valve in the communication between said two receptacles opening for delivery of liquid into said second receptacle; a conduit-in-common 30 to the two receptacles for their delivery to the carbureter; connections from said conduit-in-common, leading back toward the receptacles respectively for connection therewith at the same outlet at which the two 35 chambers are connected for delivery from the 40

first into the second, and means in the conduit mentioned operable at will alternatively for (a) cutting off both receptacles from the carbureter, (b) cutting off the first receptacle from the carbureter, leaving the second connected for delivery thereto, or (c) cutting off the second receptacle leaving the first connected for delivery thereto.

2. In combination with a vacuum fuel feeding device which comprises a bi-cameral receptacle having a primal chamber and suction connection, fuel supply connection and atmosphere inlet and which discharges by gravity into a secondary chamber; a secondary receptacle whose chamber is connected 45 with the secondary chamber of the first receptacle; means for delivery of liquid fuel from the first receptacle into the second; means for delivery from each receptacle to the carbureter; means operable at will for alternatively (a) cutting off both receptacles from the carbureter; (b) cutting off the first mentioned receptacle without cutting off the second; (c) cutting off the second mentioned receptacle without cutting off the first; and 50 a one-way-seating valve in the communication between said two receptacles opening 55 for delivery of liquid to the second receptacle.

3. In the construction defined in claim 1, 50 foregoing, the discharge connections from the receptacles respectively making junction for final delivery to the carbureter through a conduit in common, the means for alternative operation being a three-way 55 valve at their said junction.

In testimony whereof, I have hereunto set my hand at Chicago, Illinois, this 1 day of May, 1922.

LEONARD H. WHEELER.
